W. H. MOORE

WOOD TURNING LATHE

Filed Aug. 18, 1924

Fig. A.

Inventor

Ward B. Moore

by Dowling & Hague. Atty's.

Patented Dec. 20, 1927.

UNITED STATES PATENT OFFICE.

WARD H. MOORE, OF DES MOINES, IOWA.

WOOD-TURNING LATHE.

Application filed August 18, 1924. Serial No. 732,722.

The object of my invention is to provide a wood turning lathe of simple, durable and inexpensive construction, which is particularly adapted for turning out handles such as used on brooms, forks, rakes and the like.

A further object is to provide a turning lathe for the purpose above stated which may be easily and quickly adjusted to form handles for various designs.

More specifically it is the object of my invention to provide in a lathe for turning handles and the like, a series of adjustable knives which are controlled by means of a pattern cam having a means for automatically operating said cam, which may be easily and quickly adapted to form handles of various designs by simply changing the cam member.

My invention consists in the construction, arrangement and combination of the various parts of the device, whereby the objects contemplated are attained, as hereinafter more fully set forth, pointed out in my claim, and illustrated in the accompanying drawings, in which:

Figure 1 is a side elevation of my improved lathe.

Figure 2 is an end view.

Figure 3 is a detail sectional view taken on the line 3—3 of Figure 2.

Figure 4 is an end elevation of the cutter head.

Figure 5 is a detail sectional view taken on the line 5—5 of Figure 4, showing the manner in which the stock is fed to the lathe.

The numeral 10 indicates the base, one end of which is provided with upright supports 11 and 12, said supports having at their upper ends boxing members 13, said boxings being designed to receive a tubular shaft 14. The central portion of the shaft 14 is provided with a drive pulley 15. The forward end of the shaft 14 is provided with a disk 16, said disk having three openings 17 which extend parallel and adjacent to the shaft 14.

The outer end of the shaft 14 is provided with a sleeve 18 slidably mounted thereon. Said sleeve 18 is provided with an annular groove 19 and also with forwardly extending pins 20 which are in alignment with the openings 17 and designed to enter said openings in certain positions of their movement. Each of the pins 20 is provided with a slot 21 designed to receive one end of a

link 22, said link being connected therewith by means of a pivot 23.

The forward face of the disk 16 is provided with three forwardly extending lugs 24, which are in a radial line with the openings 17, each of the lugs 24 is provided with a radial groove 25. Each of the grooves 25 is designed to receive a shank 26 of the cutting knives 27. Said shank is pivotally mounted by pins 28, so that the inner ends 65 of the knives are free to swing outwardly about the pivots 28. Each of the shanks 26 is provided with an opening 29 designed to receive the outer end of the corresponding link 22, said link being secured therein by means of a pin 30. The inner end of each of the shanks 26 is flattened to form the cutting blade 27, said blade extending first 70 forwardly and toward the center, then bent outwardly and forwardly. The disk 16 is 75 designed to rotate in a counter-clockwise direction as shown in Figure 4. The blade 27 has its forward edge tapered and sharpened at 31. The knives are so arranged that if a piece of wood were placed longitudinally 80 through the tubular shaft 14 and the head rotated, an annular V-shaped groove would be formed in its outer surface.

By moving the sleeve 18 toward or from the disk 16, it will be seen that the shanks 26 will have their inner ends moved forwardly and rearwardly, which will also increase or decrease the distance between the cutting edges of the knives, so that handles of various diameters may be formed by the 90 simple operation of moving the sleeve 18 toward or from the disk 16.

In front of the tubular shaft 14 I have provided a square trough 32 which extends longitudinally and in alignment with the 95 opening in the tubular shaft, said trough being designed to receive a square stick of wood 33. The trough 32 is supported by upright members 34 from the base 10.

For feeding the stick of wood endways 100 into the cutting knives, I have provided the following mechanism:

A shaft 35 is mounted transversely above the rear end of the stick 32, while a shaft 36 is mounted transversely beneath it. The 105 shaft 35 is provided with a feed roller 37, while the shaft 36 is provided with a feed roller 38, the periphery of said rollers being preferably corrugated and designed to engage the upper and lower surfaces of the 110

stick so that as the said rollers are operated in opposite directions, the said stick will be fed endways.

Corresponding ends of said shafts 35 and 36 are provided with coating spur gears 39. The outer end of the shaft 35 is provided with a bevel gear 40 designed to be operated through a pinion 41 mounted on a horizontally and longitudinally arranged shaft 42, said shaft being mounted in suitable bearings 43 from one side of the base 10. The rear end of the shaft 42 is provided with a spur gear 44 which is driven through a pinion 45 from the rear end of the tubular shaft 14, thus providing means whereby a stock of material may be continuously fed at a uniform speed to the cutting knives, which stock will be turned to a round handle as the cutter blades are rotated, and of a diameter depending on the spacing of the cutting edge 33 of the knives.

To automatically control said knives, I have provided a yoke 46 designed to operate in the groove 19 of the collar 18, said yoke having outwardly extending pins 47 which are pivotally mounted in the free ends of a yoke 48, one end of which is pivoted at 49 to the base 10. A lever 50 is connected to the yoke 48 and extends forwardly and upwardly, the forward end of said lever being provided with a cam pin 51 designed to run in a cam groove 52 in the cam gear 53, said cam gear being mounted on a transversely arranged shaft 54. The gear 53 is operated from the top one of the gears 39 through the idler gear 55, said idler being mounted in a swinging arm 56, one end of which is pivotally mounted on the shaft 35. This provides means whereby cam gears of various diameters may be applied to the cam shaft 54 for driving the same. Cams of various shapes may also be detachably applied to the shaft 54.

Thus it will be seen that when the shaft 14 is rotated the cutters 27 will be rotated and also the cam 53 through the gearing mechanism above described. When the said cam 53 is operated, the arm 50 will be rocked, causing the sleeve 18 to move toward or from the disk 16, and in turn the cutting edges of the knives 27 may be moved toward or from each other.

By forming the cam groove 52 of various shapes, it will be seen that handles of various designs may be formed automatically as the lathe is operated. If it is desired to produce a longer handle of the same design, then the operator removes the cam gear and places a larger one in its place; or if it is desired to produce a handle of a different design, the operator removes the cam and replaces it with a pattern of a different design, all of which may be easily and quickly accomplished without making any change or adjustments in the lathe itself.

Thus it will be seen that I have provided a lathe of simple, durable and inexpensive construction, which is adapted to automatically feed and turn handles of various shapes and designs on a square stick of material, which may be easily and quickly placed within the trough provided for that purpose.

It will further be seen that I have provided an improved knife which will enable the operator to form a complete and finished handle by one movement of the stock through the trough 32 and the tubular shaft 14. That is, the handle is completed in one operation.

By providing the stock trough, it will be seen that I have provided means whereby one size stock may be used to make handles of various sizes. It will also provide means for rigidly supporting the stock while it is being turned. Handles of any desired length may be turned without chattering or springing, due to the fact that the delivery end of the trough is located near the cutting blades.

By providing a series of cutters arranged in a radial manner, I have provided means whereby work will be done very rapidly, due to the fact that a number of cuts take place each time the shaft 14 makes a single revolution, which greatly increases the speed of the work over the ordinary lathe where a single stationary blade is employed. The cutter blades being arranged in a radial and opposite manner provides means whereby a uniform lateral cutting pressure is applied to the stock. This also helps to eliminate chattering.

By providing the V-shaped knives having the forward faces extending forwardly and outwardly, I have provided means whereby the stock will be cut transversely as well as longitudinally, making a clean cut as they go. This prevents slivering and splitting.

I claim as my invention:

In a device of the class described, a tubular shaft, a cutter device secured to one end of said shaft to rotate in unison therewith, said cutter device comprising a disk having its outer face provided with a series of radially arranged guide members, a shank member pivoted to the outer end of each of said guide members, the inner end of each of said shanks being provided with a cutter knife, a sleeve slidably mounted on said shaft, a link for the inner end of each of said shanks, said links extending through said disk and longitudinally of said shaft and having their inner ends connected to said sleeve, a lever mechanism for sliding said sleeve longitudinally with said shaft and to impart movement to the inner ends of said cutters toward and from said disk and toward and from each other.
